DETACHABLE PAD FOR MEANS FOR OPERATING SEWING MACHINE FEET

Charles C. Johnsen, Poughkeepsie, N. Y.

Application November 27, 1931, Serial No. 577,683. Renewed August 9, 1933.

1 Claim. (Cl. 74—81)

An object of the invention is to provide a detachable pad for a lifter which is customarily provided for engagement by the knee of the operator for raising the foot of a sewing machine. In operating a sewing machine it is usually necessary for the operator to raise the foot from twelve to twenty-five times every minute. The lifter is operated by the operator's knee, so that both hands of the operator will be free to guide the work at the foot of the machine. With this repeated operation of the lifter by the knee of the operator, the operator becomes lame and sore, after which the lifter is sometimes banged suddenly, or more often the operator will endeavor to adjust her work without raising the foot of the sewing machine, which impairs the quality of the work. The detachable pad which is the subject matter of this application avoids these objections and difficulties and permits the operator to readily and conveniently raise the foot of the sewing machine with her knee without injuring her knee and without damage to her clothing.

Other objects of the invention are to provide an attachment for a lifter for raising the foot of a sewing machine which will protect the operator and her clothing, and which will increase production and the efficiency of the operator. The attachment is so constructed that it may be conveniently removed from the lifter to permit of the cleansing of the attachment.

A further object of the invention is to provide a pad for a knee lifter having at its rear a peripheral flap for extending over the rim of the knee lifter and at its face a sponge rubber concave pad for engagement by the knee of the operator.

Additional objects of the invention will appear in the following specification in which the preferred form of the invention is described.

In the drawing similar reference characters refer to similar parts in the several views, of which

Figure 1 is a perspective view illustrating the manner in which the detachable pad is mounted on a foot-operated member with which a sewing machine is provided,

Figure 2 is a view of the operating member for the foot of the sewing machine showing the detachable pad mounted thereon, the detachable pad being illustrated in section, and

Figure 3 is a perspective view illustrating the detachable member.

By referring to the drawing it will be seen that the sewing machine 5 is provided with the usual foot which is operated by means of a shaft 6 to

which an arm 7 is secured, a plate 8 being mounted on this arm 7 by which means the shaft 6 may be rocked. This plate 8 is positioned to be engaged by the knee of the operator of the sewing machine for raising the foot in a manner readily understood.

To avoid injury to the knee of the operator, which takes place when the operator engages the plate at short periods, a pad 9 is provided which is made detachable from the plate 8, in order that the pad 9 may be removed and may be cleansed. This pad 9 is manufactured in one piece of sponge rubber and has at its rear a peripheral flange 10 which is spaced from the body 11 of the pad and which extends substantially parallel with the face 12 of the body 11, so that this peripheral flange 10, which is of rubber and which is integral with the body 11 of the pad, may be disposed over the rim 13 of the plate. The outer face of the plate 8 is concave and the rear of the body 11 of the pad 9 is curved to conform to the curvature of the plate 8.

The face 12 of the body 11 of the pad 9 is also concave vertically and is disposed substantially parallel with the rear face of the body 11 of the pad. The pad, including its body 11 and its peripheral flange 10, is manufactured of rubber, with the flange 10 integral with the body 11 and with the body manufactured of sponge rubber and preferably the flange 10 also being manufactured of sponge rubber. It will be seen that when the knee of the operator is moved to engage the pad 9, the knee will pivot at the foot and the knee and the leg of the operator immediately below the knee will engage the sponge rubber pad 9, which will prevent a forward or rearward movement of the knee under the influence of the parts of the sewing machine with which the foot engages. This also serves to assist in stopping the sewing machine as the foot of the sewing machine is raised.

When using the pad on the plate 8, the operator will press against the face 12 of the body 11 of the pad for raising the foot of the sewing machine, which will not only protect the knee of the operator, but which will also prevent sudden shock in the parts of the sewing machine at its foot, which would be the case if there were no resilient pad between the knee of the operator and the foot of the sewing machine. Therefore, not only is the sewing machine protected by the pad which has been described, but the sewing machine is operated with less noise and without wear on the parts which is the case where there is no give or resiliency between the knee 110

of the operator and the foot of the sewing machine. The pad, therefore, acts not only as a cushion to protect the knee of the operator, but also as a cushion to prevent shocks at the foot 5 of the machine when the foot is raised.

What is claimed is:—

In an article of the class described, an integral rubber member having a face of sponge rubber for engagement by a knee of an operator, the face 10 being concave vertically to permit a broad con-

tact of the knee of the operator with the said face of sponge rubber as the leg is moved with the foot as a pivot, the rubber member having at its rear a flap extending inwardly from and all around the periphery of the member approximately parallel with the said face for disposal over the rim of a plate for lifting a foot of a sewing machine. 80
